[57] CLAIM

The ornamental design for cable clamp, as shown and described.

DESCRIPTION

FIG. 1 is a top perspective view of a cable clamp showing my new design, a portion of the loop of the clamp being broken away for compactness of illustration;

FIG. 2 is a top plan view;

FIG. 3 is a bottom plan view;

FIG. 4 is a front elevational view;

FIG. 5 is a rear elevational view thereof;

FIG. 6 is a side elevational view taken from the left of FIG. 2;

FIG. 7 is a side elevational view taken from the right of FIG. 2; and

FIG. 8 is a sectional view taken in the direction of the arrows on line 8—8 of FIG. 4.
